[57] CLAIM

The ornamental design for a fan stand, as shown and described.

DESCRIPTION

FIG. 1 is a perspective view of a fan stand showing my new design;

FIG. 2 is a front elevational view thereof;

FIG. 3 is a top plan view thereof;

FIG. 4 is a bottom plan view thereof;

FIG. 5 is a side elevational view thereof, the opposite side being a mirror image of that shown; and,

FIG. 6 is a perspective view thereof on a reduced scale shown in use.

The broken line showing of environmental structure in FIG. 6 is for illustrative purposes only and forms no part of the claimed design.
